US0D1024925S

(12) **United States Design Patent** (10) Patent No.: **US D1,024,925 S**
(45) Date of Patent: ** Apr. 30, 2024

(54) **SOLAR PANEL**

(71) Applicant: **Trina Solar Co., Ltd**, Changzhou (CN)

(72) Inventors: **Junpan Guo**, Jiangsu (CN); **Faye Lu**, Jiangsu (CN); **Shu Zhang**, Jiangsu (CN); **Le Wang**, Jiangsu (CN); **Jianmei Xu**, Jiangsu (CN)

(**) Term: **15 Years**

(21) Appl. No.: **35/516,054**

(22) Filed: **Oct. 19, 2022**

(80) **Hague Agreement Data**

Int. Filing Date: **Oct. 19, 2022**

Int. Reg. No.: **DM/226016**

Int. Reg. Date: **Oct. 19, 2022**

Int. Reg. Pub. Date: **Jan. 20, 2023**

(30) **Foreign Application Priority Data**

Apr. 28, 2022 (CN) 202230249299.X

(57) **CLAIM**

The ornamental design for a solar panel, as shown and described.

DESCRIPTION

- 3. Solar panel
- 4. Solar panel
- 5. Solar panel
- 3.1: Front
- 3.2: Back
- 3.3: Enlarged
- 3.4: Enlarged
- 3.5: Enlarged
- 3.6: Enlarged
- 3.7: Perspective
- 3.8: Left
- 3.9: Top
- 3.10: Right
- 3.11: Bottom
- 4.1: Front
- 4.2: Back
- 4.3: Enlarged
- 4.4: Enlarged
- 4.5: Enlarged
- 4.6: Enlarged
- 4.7: Perspective
- 4.8: Left
- 4.9: Top
- 4.10: Right
- 4.11: Bottom
- 5.1: Front
- 5.2: Back
- 5.3: Enlarged
- 5.4: Enlarged
- 5.5: Enlarged
- 5.6: Enlarged

(Continued)

5.7: Perspective**5.8:** Left**5.9:** Top**5.10:** Right**5.11:** Bottom

3.3 to **3.6** are enlarged views of parts A to D, respectively, in **3.1**; **4.3** to **4.6** are enlarged views of parts A to D, respectively, in **4.1**; **5.3** to **5.6** are enlarged views of parts A to D, respectively in **5.1**.
